United States Patent

Des. 239,573

Patented Apr. 13, 1976

239,573

SKI CARRIER

Patrick R. Drouillard, Windsor, Ontario, Canada, assignor to Michael J. Galla and Donald E. Rose

Filed Oct. 31, 1974, Ser. No. 519,510

Term of patent 14 years

Int. Cl. D3—99

U.S. Cl. D87—1 R

FIG. 1 is a plan view of a ski carrier showing my new design, the opposite side being a mirror image thereto;

FIG. 2 is an edge elevational view thereof as taken from line 2—2;

FIG. 3 is a side elevational view thereof in the wrapped, or in-use position;

FIG. 4 is a side elevational view as taken from line 4—4 of FIG. 3;

FIG. 5 is a perspective view of FIG. 3.

I claim:

The ornamental design for a ski carrier, substantially as shown and described.
